UNITED STATES PATENT OFFICE.

FRANK E. ETZEL, OF MONTCLAIR, NEW JERSEY.

AIR-VALVE FOR RADIATORS.

1,347,216.

Specification of Letters Patent.

Patented July 20, 1920.

Application filed April 15, 1919. Serial No. 290,172.

To all whom it may concern:

Be it known that I, FRANK E. ETZEL, a citizen of the United States, and resident of Montclair, in the county of Essex and State 5 of New Jersey, have invented certain new and useful Improvements in Air-Valves for Radiators, of which the following is a specification.

In steam heating systems utilizing radiators the latter are usually provided with valves to permit the air from the radiators to escape to enable the radiators to be properly charged with steam, but by reason of the condensation of steam therein said valves 10 very frequently become clogged with water to such an extent as to prevent the operation of the pin-valve that controls the outflowing air with the consequent disadvantage that the air does not escape from the radiators 15 and the latter are not properly charged with steam.

The object of my invention is to provide improvements in the class of valves above referred to, designed to insure draining of 20 the water from the air valve to prevent such water from clogging the passage from the radiator into the valve casing, to insure the flow of air from the radiator into and out of 25 said valve casing, whereby the radiator may 30 become properly charged with steam at all times.

My invention comprises novel details of improvement that will be more fully hereinafter set forth and then pointed out in the 35 claims.

Reference is to be had to the accompanying drawings forming part hereof, wherein

Figure 1 is a partly sectional side elevation of an air valve for a radiator embodying my invention;

Fig. 2 is a partly broken plan view of part of Fig. 1, parts of the shell being omitted; and

Fig. 3 is a detail side elevation of my improved water discharge tube.

An air valve indicated generally at A is illustrated in accordance with the well known type of valve comprising a cup-like base portion 1 to which the shell 2 is detachably secured, as by screw threads at 3, said casing having a neck 2^a containing a valve seat for the outflowing air co-operative 50 with a pin-valve 4 carried by a float 5 guided

by the stem 6. A cap 7 is detachably applied upon the neck 1^a and provided with an air 55 exit opening 7^a. Since said valve parts operate in the well known manner further detail description will be unnecessary.

At 8 is a nipple projecting from the base or cup 1 and adapted to be screwed in a 60 radiator in the usual manner for attaching the valve thereto. At 9 is indicated my improved drainage tube in tubular form shown having a laterally disposed portion located within a bore 8^a of the nipple 8 and also 65 having a depending portion which is adapted to be located within the radiator tube to which the nipple 8 is attached. The tube 9 at the inner end has a flaring portion at 9^a, shown in the form of a bell-mouth, located 70 within the cup or base 1, whereby the tube is retained in place in the nipple. The lower end of the tube 9 is also flaring or bell-mouthed at 9^b. At 9^c the tube 9 is provided with an opening or slot shown in elongated 75 form, located along the upper portion of the tube, and at 9^d is a similar elongated opening or slot at the under portion of the tube opposite the opening 9^c. At the lower bell-mouth portion the tube 9 is provided with 80 one or more narrow elongated openings or slots 9^e. The aforesaid openings serve to permit the entrance of air and steam into the tube. The tube 9 may be formed at its 85 inner end of such dimensions as to permit it to be passed through the bore in the nipple 8 from the outside inwardly into the cup 1, and the tube may then be turned around in such a position as to permit the end 9^a to be flared and widened, whereby the tube will 90 be retained movably attached to the cup as shown. After the tube has been flared, as stated, the parts may be assembled. The bore 8^a is shown outwardly tapering or flaring which has the advantage of permitting 95 the tube to be suitably manipulated when its end 9^a is being flared, and also serves to facilitate the outflow of water from the valve casing and cup. The tapering form of the bore 8^a also serves to cause water that 100 might tend to clog around the tube 9 in said bore to gather at the end of the latter and thereby be induced to flow along the tube or to be drawn into the slot or opening in the tube due to the flow of water through 105 the tube. By thus keeping the bore 8^a free

from water accumulation and clogging, the slots or openings 9^c, 9^d are also kept free and open for the entrance of air and steam into the upper portion of the tube 5 from the outside, at all times, in addition to air entering the tube from its lower open end, whereby water is permitted to run freely from cup or base 1 into and through the tube, and some of such water 10 may drain through the lower opening 9^d. A further advantage is that air and steam may enter the tube and valve casing at one place or another through such openings or slots, when a bubble of water becomes lodged in 15 the lower portion of the tube tending to close the passage therethrough. Under ordinary conditions the water would flow from cup or base 1 to the lower end of tube 9, but after most of the water had drained off there 20 might be some that would remain at said end, possibly hanging suspended at the end, within the tube, tending to clog the outlet opening and possibly closing it against entrance of air or steam. Slot or slots 9^e 25 adjacent to the lower end of the tube permit steam or air to enter the tube above such water and thus the tube is kept open at its lower part for the admission of air and steam, so that if water should gather at the 30 lower end of the tube, tending to clog it, air and steam is not prevented by such water from entering the tube.

The bell-mouth portion 9^a at the upper end of the tube provides a wide opening 35 within the cup or base 1 for the flow of water into the tube 9. Such water is frequently covered with an oily film that will not readily enter a small opening, but the bell-mouth portion 9^a of the tube 9 overcomes such objection by preventing such oily 40 water from accumulating and blocking the entrance to the tube, since the width of the opening 9^a is such as readily to permit such film to be broken to permit water to flow 45 freely into the tube. In case the water becomes lodged in the tube between slots 9^c, 9^d and the inner end of the tube, air or steam from the radiator entering the tube through a slot 9^c or 9^d, or both, will more readily displace such water due to the gradually increasing size of the opening 9^a from its inner to its outer portion adjacent to the 50 end of the tube. If the tube 9 were of the same diameter throughout to its lower end, 55 which may be termed a straight tube, only a certain amount of water could be depended upon to drip or flow from the tube and some would be liable to remain hanging at the end of the tube, and partly within the same 60 to a more or less extent, having the disadvantage of closing the tube to the passage of air and steam but the downwardly tapering or bell-mouth shape of the tube at the lower end causes the water thereat to spread

as it passes through the tube, and the water 65 that does not tend to readily drip off will gather at the widest part of the tube mouth where it may hang suspended. The advantage is that the tube is kept free from water in the depending portion except for such 70 small amount of water as may gather at the extreme lower end, and even should such water tend to clog the lower outlet of the tube for any length of time the slots 9^e above such water will admit air or steam into the 75 tube, as before stated, to prevent clogging of the latter to the detriment of the passage of air or steam.

My improvements are simple in construction and effective in use, and do not depend 80 upon capillary action to induce the flow or draining of water from the cup or base but serve effectually to cause drainage of the latter at all times, whereby the free entrance of air and steam into the valve casing is 85 maintained so that the air forced into the valve casing from the radiator may escape from such casing to permit entrance of steam to insure proper and continued charging 90 of the radiator with steam.

What I claim and desire to secure by Letters Patent is:—

1. An air valve for radiators comprising a base or cup, and a mainly impervious drainage tube communicating therewith, 95 said drainage tube having an opening in its wall to admit air and steam and having a widened entrance portion within the base or cup.

2. An air valve for radiators comprising 100 a base or cup having a nipple provided with an outwardly tapering bore, and a drainage tube having a portion located in said bore, said tube having an elongated opening within said bore.

3. An air valve for radiators comprising 105 a base or cup, and a drainage tube extending therefrom and having a depending portion provided with a flaring lower end, said tube having one or more openings adjacent to the 110 said flaring lower end.

4. An air valve for radiators comprising 115 a base or cup, a nipple provided with an outwardly tapering bore, and a drainage tube having a laterally disposed portion within said bore inclining downwardly therein and provided with a bell-mouth entrance portion within the base or cup, said tube having a downwardly extending portion provided with a flaring lower end, said 120 tube having one or more slots at its upper portion.

5. An air valve for radiators comprising 125 a base or cup, a nipple provided with an outwardly tapering bore, and a drainage tube having a laterally disposed portion within said bore inclining downwardly therein, and provided with a bell-mouth entrance

portion within the base or cup, said tube having a downwardly extending portion provided with a flaring lower end, said tube having one or more slots at its upper portion, 5 and having one or more slots at its lower flaring portion.

6. An air valve for radiators comprising a base or cup having a nipple provided with an outwardly tapering bore and a drainage

tube having a portion located in said bore 10 and having a receiving end communicating with said base or cup, said tube inclining downwardly and outwardly in said bore.

Signed at New York, in the county of New York and State of New York this 11th 15 day of April A. D. 1919.

FRANK E. ETZEL.
